US0D1030452S

(12) **United States Design Patent** (10) **Patent No.:** **US D1,030,452 S**
(45) **Date of Patent:** **** Jun. 11, 2024**

(54) **PUMP MOUNT**

(71) Applicant: **BLUE-WHITE INDUSTRIES, LTD.**,
Huntington Beach, CA (US)

(72) Inventors: **John T. Nguyen**, Fountain Valley, CA
(US); **Robert E. Gledhill, III**,
Huntington Beach, CA (US)

(73) Assignee: **BLUE-WHITE INDUSTRIES, LTD.**,
Huntington Beach, CA (US)

(**) Term: **15 Years**

(21) Appl. No.: **29/865,049**

(22) Filed: **Jul. 5, 2022**

Related U.S. Application Data

(62) Division of application No. 29/702,346, filed on Aug. 19, 2019, now Pat. No. Des. 959,238.

(51) **LOC (14) Cl.** **08-05**

(52) **U.S. Cl.** **D8/354**

(57) **CLAIM**

The ornamental design for a pump mount, as shown and described.

DESCRIPTION

FIG. 1 is a top-side isometric view of a design for a pump mount;

FIG. 2 is a front view of the pump mount;

FIG. 3 is a rear view of the pump mount;

FIG. 4 is a left side view of the pump mount;

FIG. 5 is a right side view of the pump mount;

FIG. 6 is a top view of the pump mount; and,

FIG. 7 is a bottom view of the pump mount.

The broken lines in the drawings illustrate portions of a pump mount which form no part of the claimed design.

1 Claim, 5 Drawing Sheets
